(57) **CLAIM**

The ornamental design for an inflatable water hammock, as shown and described.

DESCRIPTION

FIG. 1 is a rear, left and top perspective view of an inflatable water hammock, showing my new design;

FIG. 2 is a front, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the figures are for the purpose of illustrating portions of the inflatable water hammock and form no part of the claimed design.
